UNITED STATES PATENT OFFICE.

GIUSEPPE BERTOLINI, OF CHICAGO, ILLINOIS.

CARBID-GENERATOR.

1,318,046.

Specification of Letters Patent.

Patented Oct. 7, 1919.

Application filed May 22, 1918. Serial No. 235,916.

To all whom it may concern:

Be it known that I, GIUSEPPE BERTOLINI, a subject of the King of Italy, residing at Chicago, in the county of Cook and State 5 of Illinois, have invented new and useful Improvements in Carbid-Generators, of which the following is a specification:

This invention relates to a device for generating carbid gas for use in internal combustion engines, such as now commonly employed on automobiles, motor boats, motor 10 trucks, and the like.

Among the objects of my invention is to improve the construction of devices of the 15 kind referred to, in the several particulars as will hereinafter more fully appear, and to provide in particular a generating device which will be automatic in its operation and act to feed solid carbid into the generators proportionately to the rate of 20 consumption of the gas by the engine. A further object of my invention is to so construct and arrange the parts of the device that the same will be compact and thus permit its 25 installation in a motor car as a complete unit and dispense with the liquid fuel handling system heretofore employed on such vehicles.

The invention consists further in the matters hereinafter described and more particularly pointed out in the appended claims.

In the accompanying drawings—

Figure 1 is a diagrammatic view of a generating device embodying the features of my invention and shown connected with the intake manifold of an internal combustion engine;

Fig. 2 is an enlarged vertical sectional view taken on line 2—2 of Fig. 1;

Fig. 3 is a longitudinal sectional view of the differential pressure cylinder of my invention, the same being shown removed from the other parts of my device for the sake of clearness of illustration;

Fig. 4 is a vertical sectional view taken on line 4—4 of Fig. 6;

Fig. 5 is an enlarged transverse sectional view taken through the cut-off valve casing, to be hereinafter referred to; and

Fig. 6 is an enlarged vertical sectional view taken on line 6—6 of Fig. 4.

In the drawings, I have shown in detail a device embodying the features of my invention, and, as illustrated, the same comprises a tank 10 of any suitable form and construction and adapted to contain carbid in its solid form, either granular or pulverulent, as may be found most desirable. Said tank 10 is provided with a movable cover (not shown) to facilitate 55 filling the same. Depending from an opening into the tank 10 through its bottom wall is a pipe 11, the latter being connected with and opening into two branch pipes 12, 12, one opening into each of the generator cylinders 13, 13, as shown in Figs. 1 and 4. Each pipe 12 opens into the connected generator 13 through the top wall thereof, and serves to discharge solid carbid from the tank 10 into and upon the bottom wall of said generator. Said generators 13, 13, may be mounted on a base or stand or on the frame-work of an automobile or the like, when my device is applied thereto. For the purpose 60 of converting such solid carbid into gaseous form, I provide a water tank 14, which in the instance shown is located above the generators 13, 13 and suspended from the tank 10 by depending brackets 15, 15. Any other 65 type of supporting means may be provided for this purpose or, if found desirable, said water tank may be mounted at the required level directly upon the frame-work of the vehicle in which my complete device is installed. Said tank 14 is provided with an 70 inlet 16 to permit filling thereof. Opening into the tank 14 through the bottom wall thereof is an outlet pipe 17 controlled by manually operable valve preferably in the 75 form of a turning plug 18. Said pipe 17 is provided with two branch pipes, 19, 19, one for each generator 13 and discharging into the same through the top wall thereof. By operating the turning plug 18, water 80 may be discharged into the generators 13, 13 at the speed desired. Said generators 13, 13 are preferably vertically arranged, so 85 that they have a top wall and a bottom wall, and interposed between them is a cylinder 20, preferably horizontally arranged and having within it a slidible piston 21, as 90 shown in dotted lines in Fig. 1 and in full 95

lines in Fig. 3. Said piston 21 is designed to slide back and forth in or endwise of the cylinder 22, and is provided with a piston rod 23, the latter having an equal length extending from each side of said piston 21. Said rod 23 extends through and beyond both of the end walls 24, 24 of said cylinder 20, there being suitable packing glands 25, 25 provided in said end walls to make a leak-proof joint between such parts, but permitting said rod to slide endwise through said end walls in the movement of the piston endwise of said cylinder. Said cylinder 20 is supported between the generators 13, 13 by being connected therewith, although any other type of supporting means may be used to meet the particular requirements of each installation. Said cylinder 20 is connected at each end thereof with the generator 13 adjacent to such end, by a plurality of pipes 26, 26^a, one opening into the connected generator 13 adjacent to the upper end thereof and above the cylinder 20 and the other opening into the same generator 13 through the side wall thereof and approximately at a point midway between the upper and lower ends thereof, as shown in Fig. 1. As the carbid gas is generated in the generators 13, 13, such gas rises toward the upper end thereof, and, by having the pipes 26, 26^a arranged as shown, it follows that the gas first enters the cylinder 20 through the lowermost pipe 26^a, and again into the cylinder 20 when the gas reaches the uppermost pipe 26. The piston 21 is provided with reduced portions or bosses 27, 27 at each side thereof and which may come into contact with the end walls of the cylinder 20 for limiting the endwise movement of the piston and further to prevent the body portion of the piston from closing the adjacent ends of the pipes 26, 26^a. Any suitable means may be provided for preventing the piston 21 from turning or rotating in the cylinder 20 and further to guard against leakage between the piston and the walls of said cylinder.

To control the discharge of solid carbid into each generator 13, I provide therein a valve 28, as shown in Figs. 4 and 6. The generators 13 are made alike, so a description of one will suffice for both. Said valve 28 has movement in the arc of a circle from open to closed position, it being shown in open position in full lines in Fig. 4 and in closed position in dotted lines in the same figure. Said valve is preferably made in the shape of a square block, as shown in Figs. 4 and 5, and has its upper surface curved in the arc of the circle defining its movement, so that it may be swung into and out of position close to and closing the adjacent open end of the discharge pipe 12. Said valve is mounted in a rock shaft 29 located below the same and extending trans-

versely across the generator 13. Said shaft 29 has its ends journaled in and extending through and beyond the side walls of the generator 13. To prevent the gas generated in the generator 13 from escaping therefrom through the openings through which the rock shaft extends I provide packing glands 30 at such parts. Depending from the valve 28 is a stem 31 having a hub 32 encircling the shaft 29 and secured thereto by a set screw 33. To one end of said shaft 29 is secured an arm 34 located outside of the generator 13 and positioned in the path of endwise movement of the piston rod 23. At the other end of the shaft 29 is secured an arm 35, also located outside of the generator 13 and having applied thereto a weight 36, the latter being adjustably connected with said arm by a set screw 37. The arms 34, 35 extend downward from the shaft 29, and, as illustrated in Fig. 1, the arms 34, 34 are on the same side of the generators 13, 13 as the interposed cylinder 20, while the weighted arms 35, 35 are both on the opposite side thereof. The piston rod 23 has such a length that it extends between the free or lower ends of the arms 34, 34, and the weights 36 hold such arms against the ends of said rod. Manifestly, when said rod 23 is moved endwise with the piston 21, first in one direction and then in the other, the arms 34, 34 are swung to open and close the valves 28, 28 alternately and thereby permit an intermittent discharge of solid carbid from the tank 10 into the generators 13, 13. The parts are so proportioned with respect to each other that the rod 23 does not move far enough in either direction to permit the weights to swing the valves 28, 28 past closed positions.

Connected with the cylinder 20 are two pipes 38, 38, one opening into the cylinder 20 at each end thereof, as shown in Figs. 1 and 3. Said pipes 38, 38 are connected together at their opposed ends by a fitting 39, which in turn is connected with a hollow casing 40 by a pipe 41 having therein a check valve 42, the latter allowing gas to flow from the cylinder 20 into the casing 40, but preventing a back flow and thus avoiding back fire. In the casing 40 are arranged a plurality of transverse wire mesh screens 43, 43, through which the carbid passes for cleaning the same of excess moisture and any matter likely to be carried thereby in suspension. A pipe 44 leads from the bottom of the casing 40 into a storage tank 45, provided with a pressure gage 46, which may be equipped with a blow-off valve (not shown). To each generator 13 is connected a pipe 47, opening at one end into the upper end of the generator and at the other end into a coupling 48, from which extends a pipe 49 provided with a check valve 50 be-

tween its ends. Said pipe 49 is connected with said pipe 44. For conveying gas from the storage tank 45, there is a pipe 51 provided with a check valve 52, said pipe 51 opening into a carbureter 53. Said carbureter is in the form of a tube having its end 54 closed and its opposite end open to allow air to be drawn thereinto from the atmosphere by the suction created in the cylinders 10 of the engine 55 during the movement of the pistons therein. At the open end of said carbureter is a gate valve 56 connected with an operating rod or pull cable 57. Said cable is connected with an operating lever (not shown) provided either on the steering post of the automobile or the like, or at any place adjacent the seat of the driver. As shown in Fig. 1, the pipe 51 opens into the carbureter 53 at a point beyond the 15 valve 56. Said carbureter is also provided beyond that point with a second gate valve 58 connected with an operating rod or pull cable 59, the latter extending to an operating lever (not shown) within reach of the 20 driver from his seat. A pipe 60 opens at one end into the carbureter 53 adjacent its closed end, and at the other end into the inlet manifold 61 of the engine 55.

For the purpose of opening and closing 25 the discharge pipe 11, I provide a valve which may be operated by the driver from his seat. As shown in Fig. 5, said valve is a swinging plate 62, arranged transversely of said pipe and having at one side thereof 30 an arm 63 pivoted by a pin 64 on a lug 65 formed on or connected with the housing or casing in which the valve is located. Said valve 62 is provided at the opposite side with an arm 66, to which is connected a 35 spring 67, the latter having connection with a fixed lug 68, also secured or formed on the valve casing. An operating rod or pull cable 69 is connected with said arm 66 opposite the spring 67. Said cable extends to 40 an operating lever (not shown) positioned within reach of the driver from his seat. To guide the valve 62 in its swinging movement, I provide a slotted guide bracket 70.

The bottom of each generator casing 13 is 45 formed by a plate 71 pivoted at 72 to a lug 73 on said generator casing, so that the bottom 71 may be swung open for the purpose of flushing and cleaning out the generator. For holding said hinged bottom 71 closed, 50 I provide a spring 74 connected at one end with the bottom and at the other end with a lug 75 fixed to the side wall of the cylinder 13, as shown in Fig. 4. In the production of carbid gas in the generators 13, an appreciable amount of heat is produced, and to 55 maintain each generator casing relatively cool during the operation of the device, I make the top and side walls thereof double to form a space 76, through which circulates 60 cooling water, such space being connected by 65 pipes 77 with the cooling water circulating system of the particular car in which my device is installed.

The device herein described and shown operates as follows: The cut-off valve 62 is 65 opened, and solid carbid fed from the tank 10 into the pipes 12, 12. One of the valves 28 is in open position and the carbid is discharged into that generator 13 having its valve 28 open. Water is discharged into 70 the generator 13 by opening the valve 18, whereupon the solid carbid discharged into such generator 13 is converted into carbid gas. At such time the piston 21 is at the end of the cylinder 20 nearest the generator 75 13 having its valve 28 open. At such time the parts occupy the positions shown in Fig. 1, that is, the piston rod 23 holds the valve 28 in the right-hand generator open so that solid carbid may be discharged thereinto. 80 As the gas forms it rises toward the top of the generator and flows into the cylinder 20 through the pipes 26, 26^a and out of the cylinder 20 through one of the pipes 38. When a sufficient amount of gas has been 85 generated to create a pressure strong enough to move the piston 21, the latter is moved toward the opposite end of the cylinder 20, that is, toward the left (when the parts are viewed as shown in Fig. 1) carrying there- 90 with the rod 23 and opening the valve 28 in the opposite or left-hand generator 13, whereupon solid carbid is permitted to drop into that generator and be converted into gas 95 by water being discharged thereon. The valve 28 in the right-hand generator 13 is then permitted to move into closed position cutting off the feed of carbid thereto. The gas generated in the left-hand generator 13 flows into the left-hand end of the cylinder 100 20 and out of the same through the pipe 38. When the pressure in the left-hand end of the cylinder 20 is sufficient to overcome the now reduced pressure in the right-hand end of the cylinder 20, the piston 21 is 105 moved toward the right generator 13 to open its valve 28 and permit another charge of solid carbid to be discharged thereinto. This intermittent discharge of solid carbid, first 110 into one generator 13 and then into the other, is kept up as long as the generated gas is used to operate the pistons in the engine 55. The rapidity of action of the piston 21 will 115 of course depend upon the amount of carbid gas being consumed by the engine 55 during the operation thereof, that is, the rate of discharge of solid carbid into the generators 13, 13 will of course be proportionate to and controlled by the rapidity with which the generated carbid gas is being consumed by 120 the engine 55. The suction of the engine 55 of course draws the gas into the same from the storage tank 45, such gas of course pass-

ing through the carburetor 53, where it is mixed with air for the purpose of producing a proper explosive mixture.

Any excess gas produced in the generators 13, 13 may flow into the storage tank 45 through the pipes 47 and 49 without being first required to flow through the cleaner 40. If found desirable, the pipe 44 may be provided with a one-way opening check valve 78. To provide a proper joint between the hinged bottom wall 71 and the side walls of each generator 13, I may provide a gasket 79, as shown in Figs. 4 and 6.

Solid carbid at the present time is less expensive than liquid fuel, such as gasolene and the like, and it follows that with my mechanism a motor vehicle of the internal combustion engine type may be operated at a cost far below the cost heretofore required to run a car with gasolene or similar liquid fuel. Moreover, carbid may be carried on the car in solid form and the same converted into an explosive gas when required, thus permitting the carriage and storage of a greater amount of fuel than made possible with a liquid fuel, such as gasolene. Then again, a given quantity of solid carbid may be converted into a greater amount of available gas than an equal amount of liquid fuel, with the attendant result of gaining a greater road mileage than obtained with liquid fuel as now in general use. Other and further objects of my invention will be readily apparent to those versed in the art to which my invention appertains.

While I have shown and described herein in detail one form of a mechanism embodying the features of my invention, it is of course to be understood that the details of construction and arrangement of parts shown may be variously changed and modified without departing from the spirit and scope of my invention, and that I do not wish to be limited to the exact details of construction and arrangement of parts illustrated, except as pointed out in the annexed claims.

As an additional means for conveying carbid gas produced in the generators 13, 13 from the latter to the storage tank through the cleaner 40, I provide a pipe 80, having two branch pipes 81, 81, which open into the associated generator 13 through the top wall thereof. The other end of the pipe 80 is connected with the fitting 39, as shown in Fig. 1.

I claim as my invention:

1. A device of the character described, comprising a tank adapted to contain solid carbid, two generators connected with said tank, means for supplying water to said generators, each generator being provided with a valve for controlling the discharge of solid carbid thereinto from said tank, a

cylinder interposed between said generators, 65 pipes connecting said generators with said cylinder for supplying carbid gas thereto, a piston in said cylinder and adapted to be moved endwise thereof, first in one direction and then in the opposite direction by 70 the pressure of the carbid gas produced in said generators, a rod connected with said piston and having its ends projecting beyond said cylinder for actuating said valves alternately, and outlet pipes connected with 75 said cylinder.

2. A device of the character described, comprising a tank adapted to contain solid carbid, two generators connected with said tank, means for supplying water to said generators, each generator being provided with a valve for controlling the discharge of solid carbid thereinto from said tank, each valve having an arm, a cylinder interposed between 80 said generators, pipes connecting said generators with said cylinder for supplying carbid gas thereto, a piston in said cylinder and adapted to be moved endwise of said cylinder, first in one direction and then in the opposite direction, by the pressure of the 85 carbid gas produced in said generators, a rod connected with said piston and having its ends engaging said arms for actuating said valves alternately, outlet pipes connected with said cylinder, and means for holding 95 said arms in engagement with said rod.

3. A device of the character described, comprising a tank adapted to contain solid carbid, two generators connected with said tank, means for supplying water to said generators, each generator being provided with a valve for controlling the discharge of solid carbid thereinto from said tank, each valve having two arms, a cylinder interposed between 100 said generators, pipes connecting said generators with said cylinder for supplying carbid gas thereto, a piston in said cylinder and adapted to be moved endwise of said cylinder, first in one direction and then in the opposite direction, by the pressure of 105 the carbid gas produced in said generators, a rod connected with said piston and having its ends engaging one of the arms of each of said valves, a weight on each of the other of said arms of said valves, and outlet 110 pipes connected with said cylinder.

4. A device of the character described, comprising a tank adapted to contain solid carbid, two generators connected with said tank, means for supplying water to said 115 generators, each generator being provided with a valve for controlling the discharge of solid carbid thereinto from said tank, a cylinder interposed between said generators, pipes connecting said generators with said 120 cylinder for supplying carbid gas thereto, a piston in said cylinder and adapted to be moved endwise thereof, first in one direction

and then in the opposite direction by the pressure of the carbid gas produced in said generators, a rod connected with said piston and adapted to actuate said valves alter-
5 nately, a storage tank for the gas produced by said generators, and pipes connecting said generators and said cylinder with said storage tank.

In testimony that I claim the foregoing as my invention, I affix my signature in the 10 presence of two witnesses, this 20th day of May, A. D. 1918.

GIUSEPPE BERTOLINI.
